BATTERY-OPERATED BOOK LIGHT

Vera V. Langdon and John S. Irvine,
Indianapolis, Ind.

Application August 17, 1948, Serial No. 44,674

5 Claims. (Cl. 240—6.4)

1

This invention relates to portable book lamps, and more particularly to a book lamp of the battery-operated type which is employed to illuminate the pages of an open book.

A main object of the invention is to provide a novel and improved battery-operated book lamp which is very simple in construction, very compact in size and which may be readily attached to a book so that illumination of the book may be obtained for reading same in locations where sufficient light for reading is not otherwise available, or where it is desired to read a book without disturbing others in the vicinity, as for example, on vehicles such as trains, buses, and the like. A further object of the invention is to provide a compact portable reading lamp which is inexpensive to manufacture, rugged in construction and neat in appearance.

Further objects and advantages of the invention will become apparent from the following description and claims, and from the accompanying drawings, wherein:

Figure 1 is a perspective view of an open book showing a reading lamp according to the present invention secured thereon in operative position.

Figure 2 is a vertical cross-sectional view taken through the reading lamp of Figure 1, the lamp being shown in folded inoperative position.

Figure 3 is an enlarged cross-sectional view taken on line 3—3 of Figure 2.

Figure 4 is an enlarged elevational view of the lamp in folded inoperative position.

Figure 5 is a cross-sectional view taken on line 5—5 of Figure 3.

Figure 6 is a cross-sectional view taken on line 6—6 of Figure 3.

Figure 7 is a fragmentary perspective detail view of the hinge bar portion of the swingable arm of the lamp unit of Figure 1.

Referring to the drawings, 11 designates a casing of suitable lightweight insulating material, such as plastic or the like formed with parallel cylindrical cavities 12, 12 in which respective flashlight cells 13, 13 are positioned. As shown in Figure 3, one of the cells has its center terminal 14 directed downwardly and the other cell has its center terminal directed upwardly. Casing 11 has a bottom wall 15, to which is secured a contact spring 16, having one spring arm engaging the bottom of one cell and the other spring arm engaging the downwardly directed center terminal of the other cell. Casing 11 is formed with a central groove or channel 17 located between the cavities 12, 12.

Designated at 18 is a removable cap member having depending hollow cylindrical bosses 19,

2

19 fitting into the upper portions of the respective cavities 12, 12. The cap member 18 is removably secured to casing 11 by a U-shaped wire bail 20 whose side arms 21, 21 fit into opposing recesses formed in the respective bosses 19 and the outwardly adjacent portions of casing 11, thereby locking the cap member 18 against removal. When the bail 20 is withdrawn by moving it upwardly as viewed in Figure 5, or downwardly as viewed in Figure 6, the cap member 18 is released from the casing.

The bosses 19, 19 are formed with opposing axially aligned bores 22, 22 in which are rotatably positioned the respective end portions of a hollow shaft member 23. Rigidly secured to shaft member 23 is a hollow arm 24 extending at right angles to shaft member 23 at the mid-point thereof and being receivable in the channel 17. Secured to the end of arm 24 is a lamp socket 25 into which is threaded the lamp 26. Rigidly secured to socket 25 is the transverse bar element 27 which has secured thereto the vizor or reflector 28 overlying the lamp 26. Bar element 27 and vizor 28 are co-extensive in width with casing 11, and, as shown in Figures 3 and 4, form a longitudinal extension of the casing when the device is in its folded position with the arm 24 nested within channel 17.

Movably positioned in upwardly tapered openings 29 and 30 formed in the bottom walls of the respective bosses 19, 19, are contact balls 31 and 32. Ball 31 engages the center terminal of the upright flashlight cell and ball 32 engages the metal bottom of the shell of the inverted flashlight cell. Secured to the respective end portions of the shaft member 23, are oval contact bands 33 and 34. Bands 33 and 34 are located immediately above the respective balls 31 and 32 but do not engage said balls when arm 24 is nested in channel 17. However, when arm 24 is rotated to an outwardly extended position, as shown in dotted view in Figure 2, the tip portions of the oval bands 33 and 34 engage the respective balls 31 and 32.

45 The shaft member 23 is formed of insulating material but arm 24 is formed of metal and is hence electrically connected to the shell of socket 25. Band 33 is electrically connected to arm 24 by a wire 35 and band 34 is electrically connected to the center contact of socket 25 by a wire 36. It is, therefore, apparent that when arm 24 is rotated to an outwardly extended position, as above described, the lamp 26 will be energized by a circuit comprising the cells 13, 13 connected in series by springs 16, ball 31, band 33, wire 35, arm 24, the shell of socket 25, the lamp filament, the center

contacts of the lamp and socket, wire 36, band 34, and ball 32.

Secured to casing 11, on opposite sides of the channel 17, are depending spring clips 31, 31. Said clips are engageable over the top margins of the open covers 38, 38 of a book, in the manner illustrated in Figure 1, to hold the book in open position. As further shown in Figure 1, the arm 24 is extended forwardly over the book whereby the pages of said book will be illuminated by the light distributed from lamp 26 by the reflector 28.

When the device is not in use, it may be collapsed to the folded position shown in Figures 2, 3, and 4, whereby it may be readily carried in a pocket or handbag.

While a specific embodiment of a portable book lamp has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A portable lamp of the character described comprising a generally flat casing formed with a longitudinal recess, an arm hinged to said casing adjacent one transverse margin of said casing and being receivable in said recess in a substantially flush position therein with respect to the casing and being movable to an outwardly extended position, a lamp socket carried at the end of said arm, a battery in said casing, a switch element carried by said arm and being engageable with the battery responsive to movement of the arm to said outwardly extended position, and circuit means including said battery and switch element connected to said lamp socket.

2. A portable lamp of the character described comprising a generally flat casing formed with a longitudinal central recess, a pair of spring clips secured to said casing on the same side of the casing as said recess and spaced on opposite sides of the longitudinal central line of the casing, said clips being spaced so as to be engageable over the top marginal portions of a pair of book covers when the book is in open position, an arm hinged to said casing above said spring clips and being receivable in said recess in a substantially flush position therein with respect to the casing and being movable to an outwardly extended position, a lamp socket carried at the end of said arm, a battery in said casing, a switch element carried by said arm and being engageable with the battery responsive to movement of the arm to said outwardly extended position, and circuit means including said battery and switch element connected to said lamp socket.

3. A portable lamp of the character described comprising a generally flat casing formed with a longitudinal recess, an arm hinged to said casing adjacent one transverse margin of said casing and being receivable in said recess in a substantially flush position therein with respect to the casing and being movable to an outwardly extended position, a lamp socket carried at the end of said arm, a battery in said casing, a switch element carried by said arm and being engageable with the battery responsive to movement of the arm to said outwardly extended position, circuit means including said battery and switch element connected to said lamp socket, and a transversely extending visor carried by said arm overlying said lamp, said visor being receivable

outwardly adjacent the other transverse margin of the casing substantially flush with the casing when said arm is housed in said recess.

4. A portable light unit of the character described, comprising a casing formed with a pair of spaced cavities, each receiving a flashlight cell, and formed with a groove between said cavities, a cell in each cavity, one cell being upright and the other cell being inverted, a contact member in the bottom of the casing electrically connecting the center terminal of the inverted cell to the shell of the upright cell, a top cover removably secured to said casing, said top cover having a pair of spaced hollow bosses overlying the respective cells, the bottom walls of the bosses being each formed with an opening axially aligned with the subadjacent cell, a movable contact ball seated subadjacent each opening, a shaft member journaled in the bosses, said shaft member having secured thereto respective parallel oval ring elements overlying the respective openings and engageable with the balls seated therein, an arm rigidly secured to the shaft member at right angles thereto, said arm being receivable in said groove and being swingable to an outwardly extending position relative to the casing, the oval ring elements being out of engagement with the balls when the arm is in said groove and engaging the balls when said arm is in outwardly extended position, a lamp socket carried at the end of said arm and respective conductors electrically connecting the respective oval ring elements to the respective terminals of said lamp socket.

5. A portable reading light of the character described comprising a casing formed with a pair of spaced cavities, each receiving a flashlight cell, and formed with a groove between said cavities, a pair of spring clips secured to said casing on opposite sides of said groove, a flashlight cell in each cavity, one cell being upright and the other cell being inverted, means in said casing electrically connecting the center contact of the inverted cell to the shell of the upright cell, a shaft member rotatably mounted in the casing above the cells and having an arm secured at right angles thereto, said arm being receivable in said groove in substantially flush relation to said casing and being swingable to an outwardly extended position relative to the casing, respective oval contact rings carried by said shaft member overlying the central axial top portions of the cells, means electrically connecting one of the contact rings to the center contact of the upright cell and the other contact ring to the shell of the inverted cell responsive to the movement of said arm to said outwardly extended position, a lamp carried at the end of said arm, circuit means connecting the lamp terminals to the respective contact rings, and a visor carried by said arm overlying said lamp.
